United States Patent Office.

MILTON W. CLARK, OF WORCESTER, MASSACHUSETTS, ASSIGNOR TO R. BALL
AND COMPANY.

Letters Patent No. 80,892, dated July 28, 1868.

IMPROVEMENT IN BLIND-SLAT-TENONING MACHINE.

The Schedule referred to in these Letters Patent and making part of the same.

KNOW ALL MEN BY THESE PRESENTS:

That I, MILTON W. CLARK, of the city and county of Worcester, and Commonwealth of Massachusetts, have invented certain new and useful Improvements in Slat-Tenoning Machines; and I do hereby declare that the following is a full, clear, and exact description of the same, reference being had to the accompanying drawings, forming a part of this specification, in which—

Figure 1 represents a top or plan view.

Figure 2 represents a longitudinal central section on line A B, fig. 1.

Figure 3 represents in dark colors a cross-section on line C D, fig. 1; and

Figure 4 represents an end view of the machine.

My invention, which consists in the combination and arrangement of parts hereinafter specifically stated and claimed, relates to machinery for forming tenons upon the ends of blind-slats, and its object is to produce an organized machine by which the tenons can be cut upon the ends of the slat while the latter remains at rest.

To enable those skilled in the art to which my invention belongs to make and use the same, I will proceed to describe it more in detail.

In the drawings, the part lettered A is the bed, which is supported by the end-pieces B B. A drum, C, is supported in suitable bearings on the cross-braces *a a* of the end-pieces B B. From a pulley, C', connected with the journal of drum C, a band or belt passes around a pulley, B', on one end of the shaft D, which is supported in bearings on the tops of the end-pieces B B. Upon shaft D are two spur-gears, E E'. The hub of the latter is turned to receive the collar-piece *b*, which, in turn, is fastened to the lower side of the disk-support F, which rests upon and is fastened to the sliding pieces *c c*, which are fitted to slide on the ways 1 1 of the bed A. To the rear ends of the slide-pieces *c c* are fastened the legs 2 2, which support the bearing or box 3 of the shaft G. Upon the outer end of shaft G is fastened a pulley, *d*, around which passes a belt or band, *e*, from the drum C. The inner end of shaft G turns loose in the disk G', the periphery 4 of which rests and turns in a groove, 5, cut in the outer face of the disk-supporting piece F, as fully indicated in fig. 2.

The disk G' is grooved out on the periphery, as seen at 6, to receive the ends of guide-pieces 7, which are fastened to the stationary disk-support F'. By the use of the guide-pieces 7, the disk G' is prevented from moving longitudinally.

Disk G' has an oblong slot or hole, *f*, cut in it, and through which a quill, *g*, passes, said quill being provided with a hub or projection, *h*, which, in turn, is fastened to the outer face of the disk G' by a screw or bolt, *i*, which passes through an oblong slot, 8, whereby said quill can be set nearer to or further from the shaft G. A shaft, H, passes through quill *g*, having on its outer end a pulley, H' and on its inner end a cutter-head, I. A band, I', passes around pulley H' from a pulley, H'', on the shaft G, (see fig. 2.)

Upon the outer face of disk G' is fastened a gear, J, the teeth of which mesh into the teeth on gear E' on shaft D.

The slide-pieces *c c*, together with the stands 2 2 and disk-supporting piece F, which are fastened to said pieces, can be moved back and forth on the ways 1 1 by loosening the bolt 9 by which one of the slide-pieces is fastened to the bed.

Gear E' is made with a spline to fit a groove in the shaft D, whereby said gear can be moved back and forth on its shaft when slides *c c* are moved to adjust the cutter-head I, as may be desired. Upon the opposite end of the bed, similar and a like number of parts are supported, except that the pieces *c c*, on that end, are fastened to the bed, and therefore gear E, of shaft D, is not connected to the disk-supporting piece F on that end of the machine. The adjustments can all be made on one end of the machine.

Upon the left-hand end of the machine, in this instance, is fitted and arranged the shipping-device, as follows:

From the inside of the pulley B' project two pins, *m m*, while upon shaft D, between said pulley and

the end of the frame, is arranged a clutch-pulley, K, having a recess, n, cut in its outer side, into which fits a spiral spring, o, which passes against the side of pulley B' for the purpose of keeping its teeth or dogs, which project from its outer side, from clutching in with the teeth or dogs m m on the side of pulley B', only when pulley K is forced outwards by the slide-piece L, which is fitted to slide upon the top of the main frame of the machine, being held in place by screw 10 and guides p, y, and s, fastened to the top of the main frame.

Slide-piece L is operated by lever M, which is pivoted at 11 to the top of the main frame, and at 12 to the slide-piece L. In figs. 1 and 2, slide-piece L is shown moved out sufficiently to throw clutch-pulley K into mesh with pulley B'.

Pulley K is combined with the shaft D in such a manner, by spline and slot, that when the pulley is turned it will turn shaft D, while at the same time pulley K can be moved back and forth on shaft D, as before explained.

The inner end of the slide L is notched or cut out, as shown at 13, for the following purposes: When slide-piece L is moved out, as shown in fig. 1, a spring, 14, (see figs. 1 and 4,) fastened to the inside of the bed, springs back of the end 15 of the slide-piece L, and holds pulley K in mesh with the pulley B', until pin 16, in the side of gear J, on that end of the machine, comes around to the hook-end 17 (see dotted lines, fig. 4,) of spring 14, when the latter is sprung forward sufficiently to clear the end 15 of slide L, when spring O forces pulley K out of mesh with pulley B', the slide-piece being forced in until the shoulder 13 strikes against spring 14, and shaft D stops.

Upon the inner end of the back slide-pieces c c are fastened the standards N N, to the tops of which are hinged the slat-supports O O, to the tops of which are fastened the slat-holding springs P P, the front ends 18 18 of which are curved up, as indicated in red lines, fig. 3.

Upon the insides of the slat-supports are fastened adjustable slat-guides or stops 19 19. The front ends of the slat-supports O O rest upon the tops of the stands Q Q, fastened to the inner ends of the front slide-pieces c c, the front ends being provided with adjusting-screws 20 20, for the purpose of adjusting the slat-supports up or down, to bring the blank slat R at the proper height to be acted upon by the cutters attached to the heads I I.

It will be seen that the disks G' G' serve as the inner bearings of the shafts G G, while at the same time they serve to support the bearings of the shafts H H.

Any desired form of cutter-heads I I may be employed, and the cutters may be attached thereto in any proper manner, although I prefer to use the cutter-head for which Letters Patent were granted to me on the 31st of March, 1868.

The operation is as follows: Motion being given to the drum C in any proper manner, a rapid motion will be imparted, through belts e e, to the shafts G G, and through them, by means of pulleys H' H' and belts I' I', to the shafts H H and their heads I I. The operator now takes a blank slat, and pushes its ends under the holders P P until they strike against the stops 19 19, then moves lever M to throw slide L against pulley K, and forces it in mesh with pulley B', when a rotary motion will be imparted to shaft D, and through that to the gears J J and disk G' G'.

As the disks revolve they carry around the shafts H H and the cutter-heads I I, whereby a true tenon will be cut upon each end of the blank slat R.

By setting the cutter-heads nearer to or further from the centre of shafts G G, which can be done as before explained, smaller or larger tenons can be cut upon the ends of the slat.

It will be observed that the motion of shaft D, and consequently the motion of the gears J J and disks G' G', is stopped by the unclutching of pulley K, and that such unclutching takes place when the cutter-heads I I are down, or just the reverse from the positions shown in the drawings.

When the cutter-heads are down, the finished slat can be quickly removed, and a new blank inserted without stopping the motion of the cutter-heads.

As soon as the blank is inserted, the operator, by his hand, or by a proper treadle-arrangement to be operated by his foot, throws pulley K into clutch, when the cutter-heads I I are revolved entirely around the ends of the slat, and then stopped until the operation of removing the finished slat and inserting a new blank is completed, when the shaft D is started and the tenons cut on another slat, and so on.

Tenons may be cut on any length of slat by simply loosening screw 9 and moving the right-hand-end slides c c, and the parts connected thereto, until the heads I I have been adjusted to the proper distance apart, the belt e adjusting itself upon the drum C.

The machine may be so constructed as to have the shipping-apparatus and driving-pulley B' on the opposite end of the machine, if preferred.

The cutter-heads I I are shown in the drawings as having been run half way around after the tenons have been cut. They are shown in this position to illustrate the parts more fully.

Having described my improved machine for cutting tenons on the ends of slats for blinds and other purposes, what I claim therein as new and of my invention, and desire to secure by Letters Patent, is—

1. The combination, with the cutter-head, disks, and mechanism for imparting to them a rotary motion, of the cutter-heads and their shafts, mounted eccentrically in said disks, together with mechanism for revolving the cutter-heads in the manner described, so that the said cutter-heads shall not only have a rotary movement upon their own axes, but shall also revolve around the axes of their supporting-disks, substantially as and for the purposes set forth.

2. The combination, with the disks G' and shafts G, imparting motion to the eccentric-cutter heads, and running loosely in said disks, of the bearing-supports 2 and annular disk-supports F, substantially as and for the purposes set forth.

3. The combination, with the disks G' and cutter-head shafts, of the adjustable quill-bearings for supporting said shafts, substantially as and for the purposes set forth.
4. The combination, with one of the annular disk-supports, F, and gear E', of clasp or guide-piece b, mounted loosely upon the hub of said gear, substantially as and for the purposes set forth.
5. The combination, with one of the gears, J, and the shipper or slide, of a hooked spring, constructed and operating in connection with the said gear and shipper, in the manner set forth.

MILTON W. CLARK.
